CLAIM

The ornamental design for handgun rest, as shown and described.

DESCRIPTION

FIG. 1 is a perspective view of a handgun rest, as seen from the top, right side, showing my new design;

FIG. 2 is a top, plan view;

FIG. 3 is a right side elevational view, the appearance from the left side being a mirror image thereof;

FIG. 4 is a bottom plan view;

FIG. 5 is a front elevational view;

FIG. 6 is a rear elevational view; and,

FIG. 7 is a perspective view of the handgun rest, as in FIG. 1, showing in phantom lines a handgun positioned thereon. The material in phantom lines is intended to illustrate the utility of the handgun rest and forms no part of the claimed design.
